UNITED STATES PATENT OFFICE

2,582,992

SANITARY HAIRBRUSH OR DUSTER

Frank C. Hergert, Buffalo, N. Y.

Application August 11, 1947, Serial No. 767,873

1 Claim. (Cl. 15—194)

1

This invention relates to new and useful improvements in brushes or dusters and the primary object of the present invention is to provide a brush or duster for use in barber shops, for use in applying powder to infants, as a household duster, or the like wherein the duster head is preferably of a tissue, crepe, other types of paper, cloth, feathers, hair, string, plastic or any other pliable material construction so that the same may be discarded after use without effecting an appreciable cost to the user.

A further object of the present invention is to provide a brush or duster embodying novel means for retaining the bristles thereof in a closed and compact position when not in use.

Another important object of the present invention is the provision of a brush or duster so designed as to permit the duster head thereof to be quickly and readily applied to or removed from the handle of the device.

A still further aim of the present invention is to provide a brush or duster that is simple and practical in construction, neat and attractive in appearance, quite inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a plan view of the blank forming the duster head embracing member;

Figure 2 is a perspective view of the elements forming the duster head;

Figure 3 is a front elevational view of a duster constructed in accordance with the present invention, and with parts thereof broken away and shown in section;

Figure 4 is a front elevational view showing the embracing member applied to the duster head; and,

Figure 5 is a perspective view of the blank forming the wrapper for the duster head in slightly modified form.

Referring now to the drawings in detail, wherein for the purpose of illustration, there is disclosed a preferred embodiment of the present invention, the numeral 14 represents the duster head generally comprising a plurality of elongated strips 16 of crepe paper, tissue paper, plastic or any other suitable inexpensive strips of flexible material that form the bristles for the dusterhead. It is preferred, that the strips or

2

bristles be made from sheets of the above mentioned material. The method of making slits in the material, to form the strips, may best be accomplished by the use of a suitable machine wherein a plurality of layers of juxtaposed sheets are stacked to be cut by the machine to provide the desired strips. However, it should be noted that pieces of cord, feathers or the like may also be employed to formulate the desired strips or bristles without reducing the effect thereof. A group of these strips are then loosely packed together in cylindrical form, as shown in Figure 2, and are held in a compact position by a cylindrical wrapper or closure designated generally by the numeral 18, embracing the bristles, as shown best in Figure 4 of the drawings.

It is preferred, that this wrapper be formed from a substantially rectangular blank, as shown in Figure 1 of the drawings, and that the wrapper be provided with a plurality of transversely spaced aligned slits or weakened portions 20. A finger gripping tab or portion 22 projects outwardly from one edge of the sheet adjacent slits 20 facilitating the removal of an intermediate portion 24 of the wrapper from itself. Also, longitudinally spaced aligned slits or weakened portions 26 are provided in the wrapper communicating with slits 20 at right angles, with a tab or finger gripping portion 28 adjacent these last mentioned slits facilitating the removal of the lower portion 32 of the wrapper from the upper portion 30. When the bristles and the wrapper are in the form of a cylinder as shown in Figure 4, it is merely necessary to insert the upper portion 30 of the wrapper and the bristles into a tapered bore 34 provided in one end of a suitable handle 36. This bore is provided with internal threads 38 either annularly or spirally formed, facilitating frictional gripping of the wrapper and the bristles within the bore upon a slight inward twisting movement of the wrapper within the bore.

Having thus applied the bristles and wrapper in the bore, to remove the wrapper it is merely necessary to pull tab 22 outwardly, and separate the weakened portion 22 and the intermediate portion 24 is removed from the wrapper. Then, by pulling tab 28 toward the handle, the lower portion 32 of the wrapper is removed from the upper portion 30, exposing the bristles for use, as shown in Figure 3.

Reference is now directed to Figure 5, wherein there is disclosed a wrapper 40 for the bristles in slightly modified form. In this embodiment, 55 the wrapper blank is in substantially rectangu-

lar form having its longitudinal edges folded inwardly upon each other and secured thereto, to provide a cylindrical element that embraces the bristles to hold the same in a compact form. A transverse rip cord 42 is secured to the inner face of the wrapper 40 opposing a weakened portion in the wrapper with one terminal portion 44 of the cord projecting outwardly from one edge of the wrapper. Also, the wrapper is provided with a longitudinal rip cord 46 intersecting the transverse rip cord 42 at right angles, and opposing a longitudinal weakened portion in the wrapper. One terminal portion 48 of the cord 46 projects outwardly of the wrapper to facilitate convenient bi-secting of the lower portion 50 of the wrapper from the upper portion 52.

Obviously, any other suitable means may be employed whereby the cover may be separable from the bristles for quickly and readily exposing the bristles for instant use, without deviating from the scope of the present invention. However, it has been found that by introducing means for separating the upper portion of the wrapper from the lower portion and then bi-secting the lower portion of the wrapper, the bristles will be exposed in the minimum time without in any way destroying any of the bristles.

The general idea of the above invention is to provide a brush used by barbers, beauticians or anyone desirous of having a sanitary brush, which may be conveniently stored and readily accessible. After the brush has been used once on an individual, the brush or duster head is then discarded and replaced by a new sanitary filler brush or head formed of the above materials.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even

though there is herein shown and described a preferred embodiment of the invention the same is susceptible to certain changes fully comprehended by the spirit of the invention as herein described and the scope of the appended claim.

Having described the invention, what is claimed as new is:

A sanitary duster comprising a plurality of strips of sheet material forming bristles and having inner end portions, a wrapper embracing said bristles and including an inner end portion disposed about the inner end portions of said bristles, a circumferentially disposed weakened area provided in said wrapper adjacent the inner end portion of said wrapper, a further weakened area provided in said wrapper and intersecting the first named weakened area, a first rip cord secured to the inner surface of said wrapper and against the first mentioned weakened area, said first rip cord having an end projecting from the wrapper for removing the first mentioned weakened area provided in said wrapper, and a further rip cord secured to the inner surface of said wrapper and against said further weakened area, said further cord having an end extending from said wrapper.
